UNITED STATES PATENT OFFICE.

JESSE PERKINS MILLER, OF HOUMA, LOUISIANA, ASSIGNOR OF ONE-HALF TO WILLIAM R. CONKLIN, OF JENNINGS, LOUISIANA.

DEVICE FOR EXTRACTING CORES FROM WELLS.

Application filed June 21, 1923. Serial No. 646,841.

To all whom it may concern:

Be it known that I, JESSE P. MILLER, a citizen of the United States, residing at Houma, in the parish of Terrebonne and State of Louisiana, have invented a new and useful Device for Extracting Cores from Wells, of which the following is a specification.

This invention relates to a device for extracting cores from wells while they are being drilled, without removing the drilling stem from the well.

The general object of the invention is to provide a device of this type which is especially designed for use in connection with rotary drills, and which is so constructed as to overcome many of the difficulties experienced in obtaining cores, especially where the formation is soft.

10 A further object of the invention is to provide a device by means of which the core barrel may be hoisted or lowered while the slush pump is running, thereby overcoming the tendency of the drill stem to become 15 "frozen" or stuck. With the present invention not only may a continuous core be obtained of the formation through which the well is drilled, but it may be obtained in larger sections than can be obtained by devices now in use, thus making it necessary 20 to remove the cores less frequently.

These objects are attained by a device which is simple in its construction and has few parts. It has no latches for holding the 25 core barrel in place which are always liable to get out of order, but the core barrel is seated and held in place within the drill stem by hydraulic pressure induced by the operation of the slush pump.

30 The construction of my invention and the principles of its operation will be more clearly understood from the following detailed description taken in connection with the accompanying drawing which illustrates the 35 invention in its preferred form.

In the drawing:

Figure 1 is a vertical sectional view through the lower end of the drill stem with the core barrel in place.

40 Figure 2 is a view partly in elevation and partly in section of a special swivel forming part of the invention.

Figure 3 is a horizontal section on the line 3—3 of Figure 1.

Figure 4 is a vertical sectional view showing the improved core protector, which may be used in connection with the invention.

Figure 5 is a vertical sectional view similar to Figure 1, showing the improved core protector in assembled relation to the core barrel and drill stem.

Referring in detail to the drawing, 5 denotes the lower end of a drill stem, to which a bit body 6 is connected by means of a drill collar 7. The drill stem is of the usual tubular construction, and water, mud or other flushing fluid is forced downwardly therethrough by the slush pump, and is expelled through the flushing holes 8 in the bit body to remove the cuttings of the bit blade 9 carried by the lower end of the bit body, or to prevent the walls of the well from caving in, as will be understood by those familiar with the drilling of deep wells. The parts thus far described are of the usual construction.

55 In carrying out my invention the core cutting shoe 10, which is secured to and projects below the lower end of the bit body 6, is provided with a bore 11 through which 60 the core is received, and at its upper end is provided with an enlarged upwardly flared socket 12 adapted to form a seat for the tapered lower end 13 of a core barrel 14. The core barrel, near its upper end, is formed 65 with an inwardly extending valve seat 15 having a central opening 16, which is normally closed by a ball valve 17. The wall of the core barrel extends a short distance above the valve seat 15 to form a 70 valve chamber 18, the upper end of which is closed by a downwardly tapered core-barrel head 19. This head 19 keeps the pump pressure off of the core while it is being cut, and valve 17 prevents pressure from reaching 75 the top of the core, while the core barrel is being lifted from its seat.

The upper end of the bit body 6 has a threaded socket 20 for receiving the lower end of a core barrel housing 21, which surrounds the core barrel and is concentric therewith, and slightly spaced therefrom. The upper end of the housing 21 is outwardly flared, as shown at 22, and forms a seat

for receiving the tapered core-barrel head 19. The valve chamber 18 is provided with a vent 23, through which the water may be expelled from the core barrel as the core 5 rises therein, and this water may in turn be vented from the housing 21 through a vent 24 in the bit body 6.

When the core barrel is lowered into the drill stem, the seating of the same in the 10 seat 12 and 22 is facilitated by the hydraulic pressure induced by the slush pump, and the valve 17 prevents any pump pressure from reaching the core. A very soft formation, therefore, will stand up within the 15 core barrel, and when the same is lifted the pressure in the lower end of the core barrel will retain the core therein. Any small particles which are dislodged from the sides of the core will become wedged against the 20 lower tapered portion 18 and assist in retaining the core within the barrel. Loose sand will pack in the barrel and remain in it while being hoisted.

In Figures 4 and 5, the core barrel 14^a 25 is perfectly cylindrical in shape, and provided at its lower end with a reduced portion 25 having an internal bore 26 of slightly less diameter than the diameter of the core barrel, and forming at its upper end a 30 shoulder 27, on which rests a tubular core protector 28. This core protector receiving the core as it rises, tends to prevent the same from packing in the barrel, and when the core becomes packed in the protector 28, the 35 latter rises so that the drilling may still be continued without withdrawing the core until the core packs in the barrel 14^a below the protector. Thus, a considerably longer core can be obtained in soft formation than 40 could be obtained with an ordinary core barrel.

The core-barrel head 19 is formed with an upwardly projecting stem 29, which may be secured to a socket or fishing tool 30 carried 45 at the lower end of a hoisting line 31, whereby the core barrel may be hoisted or lowered when desired.

The upper end 32 of the drill stem is secured in the usual manner by a collar 33 to 50 a water swivel 34, and the construction of the latter is modified to permit the core barrel to be raised and lowered by the hoisting line 31, while the slush pump is running. This modification includes the substitution 55 of a T 35 for the usual connection between the swivel and the pipe 36 leading from the pump, and the upper outlet of this T is provided with a connection 37, which is in alignment with the drill stem, and provided with 60 a central opening 38 sufficiently large to permit the hoisting line 31 to pass freely therethrough. A branch 39 is provided for discharging any waste water which is forced through the opening 38 during the operation 65 of the slush pump.

The above described swivel of special construction is used whenever there is danger of the drilling stem freezing or sticking while the core is being withdrawn. In using this special swivel the slush pump continues 70 to operate until the core barrel is drawn to the surface. The swivel is then unscrewed from the collar 33, and the core barrel removed from the drill stem to obtain the core, after which the core barrel is again placed 75 within the drill stem, and the slush pump may be again operated while the core barrel is being lowered.

From the foregoing description, it will 80 be noted that my improved core barrel is particularly designed to obtain perfect cores where the formation is soft, and by using the core protector 28, or several of these core protectors one within the other, a core may 85 be obtained of greater length than has heretofore been possible without destroying the formation. It will not be necessary to remove the drill stem when the core is being removed from the well, and by using the 90 improved swivel this may be done in the softest formations without stopping the 95 operation of the slush pump for any appreciable time, and consequently without any danger of the drill stem becoming stuck.

While I have shown and described the 95 specific construction of one form in which the invention may be embodied, it is to be understood that this is merely illustrative and that various modifications may be made 100 therein without departing from the principles of the invention or sacrificing any of the advantages thereof.

What is claimed is:—

1. In a well drilling device, the combination with a tubular drill stem having a 105 tapered seat within the lower end thereof, of a core barrel fitting in said seat, and adapted to be held therein by hydraulic pressure.

2. In a well drilling device, the combination of a tubular drill stem, a cylindrical housing within the lower end of the stem and having at its upper end a tapered seat, and a core barrel adapted to be contained within said housing and having a head fitting 110 said seat and adapted to be held therein by hydraulic pressure.

3. The combination with a tubular drill stem, of a core barrel supported within the lower end thereof, a swivel for supporting the 115 drill stem and introducing water under pressure into said stem, and means for raising and lowering said core barrel within the stem while the water is being introduced through the swivel.

4. The combination of a tubular drill stem having a tapered seat within its lower end, a core barrel having its lower end fitting 120 said seat and having an enlarged tapered head, a housing supported within the drill 125

- stem and having a tapered seat at its upper end for receiving the core-barrel head, and means for introducing hydraulic pressure into the drill stem, said pressure being adapted to hold the core barrel on said seats.
- 5 5. In a device of the character described, a tubular drill stem, a core barrel removably held in the stem, means for introducing liquid pressure into the stem, and means for 10 raising and lowering the core barrel within the stem while said liquid pressure is being introduced.
6. The combination with a tubular drill stem and a water swivel for rotatably supporting the same, of a core barrel adapted to be received within the stem, said swivel having a vertical passageway through which a hoist line may pass for raising and lowering the core barrel, while the interior of the 15 stem is subjected to hydraulic pressure.
7. In a device of the character described, the combination of a tubular drill stem, a bit body secured to the lower end thereof, a cylindrical housing secured to the bit body 20 and extending upwardly into the drill stem, a core barrel adapted to seat within the housing, means for venting the core barrel into the housing, and means for venting the housing into the drill hole outside the stem.
- 25 8. In a device of the character described, the combination of a tubular drill stem and bit body, a core cutting shoe secured to the lower end thereof, a cylindrical housing secured to the bit body and extending upwardly into the drill stem, said housing and core cutting shoe having tapered seats, a core barrel having its lower end tapered to fit the seat in the core cutting shoe, and a tapered plug forming the head of the core barrel and 30 fitting the seat in the housing.
9. In a device of the character described, the combination of a tubular drill stem and bit body, a core cutting shoe secured to the lower end thereof, a cylindrical housing secured to the bit body and extending upwardly into the drill stem, said housing and shoe having tapered seats, a core barrel having tapered surfaces adapted to rest on said seats, said barrel having a valve chamber 35 and check valve at its upper end, a vent through the side of the valve chamber into the housing, and a vent through the bit body establishing communication between the interior of said housing and the drill hole outside the drill stem.
10. In a device of the character described, the combination of a drill stem, a core barrel supported by the drill stem and having its lower end contracted, and a core protector loosely held within the core barrel, and comprising a cylindrical casing shorter than the core barrel and of smaller diameter.
- 60 11. In a device of the character described, the combination with a tubular drill stem having a tapered seat in the lower end thereof, of a core barrel fitting in said seat and adapted to be held therein by hydraulic pressure, said barrel having a check valve, a vent at its upper end, and a core protector freely movable within the barrel, and comprising a 65 cylindrical casing shorter than the barrel and of smaller diameter.
12. In a device of the character described, the combination of a drill stem, a core barrel having its lower end provided with a reduced portion having a bore of less diameter than the diameter of the core barrel thereby defining a shoulder, and a tubular core protector resting on the shoulder and adapted to receive the core, said core protector extending upwardly within the core barrel and of less diameter and shorter than the same.
- 75 13. The combination of a tubular drill stem having a seat, a cylindrical housing within the same having at its upper end a flared socket, a core barrel within the housing having its lower end engaging the seat of the stem, a valve seat near the upper end of the core barrel, a valve chamber above the valve seat, a valve in the valve chamber 80 to rest on said seat, and a core barrel head closing the upper end of the valve chamber and carried by the core barrel and engaging the flared socket of said housing.
- 85 14. The combination of a tubular drill stem having a seat, a cylindrical housing within the same having at its upper end a flared socket, a core barrel within the housing having its lower end engaging the seat of the stem, a valve seat near the upper end of the core barrel, a valve chamber above the valve seat, a vent for the valve chamber, a valve in the valve chamber to rest on said seat, and a core barrel head closing the upper end of the valve chamber and carried 90 by the core barrel and engaging the flared socket of said housing.
- 95 15. In testimony that I claim the foregoing as my own, I have hereto affixed my signature.

JESSE PERKINS MILLER.
